(57) **CLAIM**

The ornamental design for a garment having a defined crotch opening with an overlapping flap as shown and described.

DESCRIPTION

FIG. 1 is a front perspective view of a garment having a crotch opening with overlapping flap showing my design;
FIG. 2 is a front view thereof;

FIG. 3 is a rear view thereof;
FIG. 4 is a side view thereof;
FIG. 5 is a side view thereof, opposite that shown in FIG. 4;
FIG. 6 is a top view thereof;
FIG. 7 is a bottom view thereof;
FIG. 8 is a front perspective environmental view of the garment having a crotch opening with overlapping flap shown with a urination device;
FIG. 9 is a front perspective view of another embodiment of the garment having a crotch opening with overlapping flap showing the design;
FIG. 10 is front view thereof;
FIG. 11 is a rear view thereof;
FIG. 12 is a side view thereof;
FIG. 13 is a side view thereof, opposite that shown in FIG. 12;
FIG. 14 is a top view thereof;
FIG. 15 is a bottom view thereof;
FIG. 16 is a front perspective environmental view of the garment having a crotch opening with overlapping flap shown with a urination device;
FIG. 17 is an enlarged bottom view of the garment having a crotch opening with overlapping flap that is included to depict the design of the garment having a crotch opening in a partially open configuration;
FIG. 18 is an enlarged bottom view of the garment having a crotch opening with overlapping flap that is included to depict the design of the garment having a crotch opening in a fully open configuration;
FIG. 19 is a front perspective view of another embodiment of the garment having a crotch opening with overlapping flap showing the design;
FIG. 20 is front view thereof;
FIG. 21 is a rear view thereof;
FIG. 22 is a side view thereof;
FIG. 23 is a side view thereof, opposite that shown in FIG. 22;
FIG. 24 is a top view thereof;
FIG. 25 is a bottom view thereof; and,
FIG. 26 is a front perspective environmental view of the garment having a crotch opening with overlapping flap shown with a urination device.
The broken lines shown in the drawing views are included for the purpose of illustrating portions of the garment having

(Continued)

a crotch opening with overlapping flap that form no part of the claimed design. The garment having a crotch opening with overlapping flap is shown with a symbolic break in length. The appearance of any portion of the article between the break lines forms no part of the claimed design. The broken lines showing fingers in FIGS. 17 and 18 are included for the purpose of depicting the garment having a crotch opening with overlapping flap in an environmental configuration.

1 Claim, 23 Drawing Sheets
